WITNESS:

Edwin F. McKee
T. L. Moorehead

UNITED STATES PATENT OFFICE.

PETER J. LUTTRELL, OF PORTLAND, MAINE.

CLAW HAMMER.

1,410,407.

Specification of Letters Patent. Patented Mar. 21, 1922.

Application filed February 8, 1921. Serial No. 443,395.

To all whom it may concern:

Be it known that I, PETER J. LUTTRELL, a citizen of the United States, residing at Portland, in the county of Cumberland and 5 State of Maine, have invented new and useful Improvements in Claw Hammers, of which the following is a specification.

This invention relates to hammers and has for an object the provision of means adapted 10 to be associated with a claw hammer for the removal of nails, the construction being such as to exert a pull directly in line with the length of the nail so as to avoid bending the latter and to reduce the amount of pull 15 necessary to effect the removal, to a minimum.

Another object is the provision of an adjustable plunger adapted to be mounted in the head of the hammer and capable of 20 being projected beyond the same, together with novel means for holding the plunger in adjusted position.

Other objects and advantages of the invention will appear as the following description is read in connection with the accompanying drawings:

In the drawings:—

Figure 1 is a side elevation of a hammer with the invention applied thereto.

30 Figure 2 is an end view of the same.

Figure 3 is a longitudinal sectional view.

Figure 4 is a detail perspective view of the plunger removed from the hammer.

Referring to the drawings in detail, where- 35 in like characters of reference denote cor- responding parts, there is illustrated a ham- mer which includes a head 10 and a handle 11, the former being provided with the usual claw 12 having a transversely arranged

40 opening 13. One end of the opening is pro- vided with a seat 14 which is adapted to re- ceive a foot 15 secured to one end of a plunger 16. The head 15 is preferably pro- vided with a rubber cap 17 for engagement

45 with the surface of the material from which the nail is to be removed, the purpose being to prevent marring the said surface during the operation of removing the nail. Extending from the opening 13 is a tubular mem- ber 18 within which the plunger 16 is adapt- ed to extend and which houses a spring 19 whose function is to project the plunger beyond the hammer head.

50 In order to hold the plunger against the action of the spring 19, there is provided a bolt 20 which operates within a slot 21 also

provided in the hammer head, this bolt ex- tending longitudinally of the head and at right angles to the plunger 16. The plunger 16 is provided with a longitudinally extend- 60 ing groove 22 in which the bolt 20 operates, the said groove acting as a guide for the bolt and preventing rotation of the plunger during its longitudinal movement. In addi- 65 tion, the plunger is provided with spaced sockets 23 which communicate with the groove 22 and which are adapted to receive the bolt 20 so as to hold the plunger against movement. The bolt 20 is normally forced into engagement with the sockets 23 by 70 means of a spring 24 and in order to hold the bolt against the action of this spring there is provided a latch 25. This latch is formed at one end with a right angled 75 extension 26, which operates in a socket 27 formed in the bolt 20, the said socket being of a size to permit the right angled ex- tremity 26 of the latch to be rotated therein with the shank of the latch as a center. This shank is mounted for rotation and has 80 secured to its outer end a pivoted handle 28, which is adjustable upon its pivot and held in adjusted position by a spring 29.

When the parts are in the position shown in Figure 2, the bolt 20 will be held in en- 85 gagement with one of the sockets 23 so that the plunger is held against movement. Through the medium of the handle 28, the latch may be given a quarter turn so that the right angled extremity 26 will lie trans- 90 versely of the hammer head and permit the bolt 20 to be actuated. By giving the latch an additional quarter turn the right angled extremity 26 will be in the position reverse 95 from that shown in Figure 2, whereupon the bolt 20 will be held against engagement with the plunger 16.

The invention is susceptible of various changes in its form, proportions and minor details of construction and the right is here- 100 in reserved to make such changes as properly fall within the scope of the appended claims.

Having described the invention what is claimed is:—

1. The combination with the handle and 105 the claw head secured thereto and provided with a socket aligned with said handle, of a plunger movably mounted in said socket and provided with a foot, a cushion for said foot, a spring for normally forcing the foot be- 110 yond the head of the hammer, a spring ac- tuated bolt arranged within the hammer

head and an operating handle pivotally mounted upon said head and connected to the bolt, whereby the latter may be restricted to release the plunger or engaged with the latter to hold the said plunger against movement.

2. The combination with a handle and a claw head secured thereto and provided with a socket aligned with said handle, of a plunger movably mounted in the socket and

provided with a foot, a spring for normally forcing the foot beyond the head of the hammer, means located within the hammer head for holding the plunger against movement and a latch also located within the hammer head and engageable with the plunger holding means for locking the same into or out of engagement therewith.

In testimony whereof I affix my signature.

PETER J. LUTTRELL.
